CREEL ACCESSORY

Maurice G. Beal, Portland, Oreg.

Application June 29, 1939, Serial No. 281,939

4 Claims. (Cl. 43—31)

This invention relates to improvements in creel accessories and especially is concerned with a novel tackle box suited to be attached either within upper parts of the creel proper or to the closed creel top.

A want has been felt for a tackle box which might be carried by fishermen, preferably by attachment to parts of a creel in a manner such that the customary use of the creel is not interfered with while easy access to the tackle in the container is permitted. It is an object of the present invention to provide a creel accessory of this type, namely a tackle container which, when used in conjunction with a creel, does not interfere with the usual use thereof and which also permits the carrying of relatively large quantities and varieties of tackle disposed within the container in an arrangement suited for ready use by the fishermen.

Another object of the present invention is to provide a novel tackle container including a cover for same which tends to remain, that is to say, is held in either open or closed position, whereby removal of the tackle from the container is facilitated, likewise protection of tackle within the container, by maintaining the cover in tightly closed position, is promoted.

Another object of the present invention is to provide a type of container which, when the creel is not filled, can be mounted in the upper inner parts of the creel without interfering with the use thereof but which, upon those rare occasions when the creel is filled, may be exteriorly attached to the top thereof likewise without interfering with the use of the creel.

A feature of the novel creel accessory according to this invention is that it may be used in conjunction with substantially all conventional types of creels irrespective of small variations in sizes and proportions of the creels.

An advantage of the type of creel accessory according to this invention is its comparative simplicity of construction and essentially universal adaptability which, suiting it to the requirements of mass production, result in concomitant low cost of manufacture.

Other objects, advantages and features of the novel creel accessory according to this invention will be apparent to those skilled in this art during the course of the following description.

Regarded in certain of its broader aspects, the creel accessory according to the present invention comprises a fishing tackle container attachable to upper marginal portions of a creel comprising an essentially flat box conforming in shape

to the conventional outline of upper parts of a creel, means for supporting the box within the upper portion of a creel, and means for attaching the box to the closed top of a creel.

In order to facilitate a fuller and more complete understanding of the matter of the present invention a specific embodiment thereof herein illustrated will be hereinafter described, it being clearly understood, however, that the illustrated embodiment, although presently preferred, is provided solely by way of example of the practice of this invention and not by way of limitation thereof except insofar as the invention is recited in the subjoined claims.

Referring now to the drawing,

Figure 1 is essentially a perspective view of a creel showing the tackle container of the present invention in position of use therein,

Fig. 2 is essentially a top plan view of the novel tackle container according to the present invention,

Fig. 3 is likewise a top plan view of the tackle container according to this invention but with the cover in raised or opened position,

Fig. 4 is a bottom view of the container illustrated in Figs. 2 and 3,

Fig. 5 is a side elevational view of the container mounted on the creel cover,

Fig. 6 is a fragmentary vertical sectional view illustrating details of the hinge construction of the container,

Fig. 7 is a detail elevational view of one of the fastening elements, and

Fig. 8 is a perspective view of another fastening element.

Referring now especially to Figs. 2, et seq., the tackle container generally designated by the numeral 10 comprises a substantially flat shallow box having a bottom 11 and sides 12 and provided with a top 13 mounted on the rear side portion by hinges generally designated by the numeral 14. Referring especially to Fig. 6, it will be noted that the rear portion of the top 13 is bent to provide cams 13a and 13b against which presses the resilient arm 14b mounted on the rear side 12 essentially as shown. It will be evident that when the cover is in lowered or closed position as illustrated in Fig. 2, the resilient arm 14b presses against the cam surface 13a thereby at least tending to hold the cover in closed position, whereas, when the cover is in opened or raised position, the resilient arm 14b presses against the cam surface 13b, thereby at least tending to hold the cover in the mentioned position.

The interior of the box hereinabove described

is subdivided into a plurality of compartments by partitions some of which are designated by the numeral 15. An opening 13c is provided in the top 13 positioned above a similar opening 11a formed in the bottom 11, the last mentioned opening being provided with downwardly extending flanges essentially as shown in Fig. 5 registerable with the first opening in the creel top as will hereinafter more clearly be apparent, 10 whereby a passage is provided through the tackle box to permit fish to be placed in the creel without removing the box from position of use.

A plurality of downwardly extending lugs 16 are mounted upon the sides 12 of the box in a 15 manner suited to receive and embrace the upper side portions of a creel when the container is positioned therein as illustrated in Fig. 1.

A pair of laterally sliding members 17, having longitudinally extending slots 17a formed therein and provided on one end with hook or claw formations 17b, are mounted on the rear of the bottom 11 essentially as shown in Fig. 4 by fastening means 17c whereby the members are 20 permitted free movement laterally outwardly to positions shown in phantom in Fig. 4. Openings 17d, formed in the opposite ends of the members 17, receive the ends of a coiled resilient tensioning element 18 whereby the hooks or claws 17b are resiliently pulled toward each other.

30 An appropriate anchor 19 carrying an extensible member 20, normally held in retracted position by the compression spring 21, serves as mounting means for the fastening element 22 which is provided with hook formations generally designated by the numeral 22a for engagement with portions of a creel top as hereinafter will more clearly be apparent.

Having thus described the structural features of the novel container according to the present 40 invention, the use thereof will next be described. When the container is to be mounted within upper portions of the creel A, the top A' of the creel is opened and the container positioned therein with the lugs 16 receiving and embracing the upper parts A' of the creel substantially as shown in Fig. 1. When so positioned, access may be had to the tackle within the container by raising the creel lid A'' and the cover 13 of the container. It is to be noted that inasmuch as the openings 11a and 13c formed in the bottom and top of the container register with the opening a in the creel top A'', fish may be disposed within the creel in the usual manner.

Referring now particularly to Fig. 5, when the 50 tackle container is to be attached in superimposed relationship to the creel top, the creel is closed and the sliding members 17 moved against the tension of the resilient element 18, thereafter being permitted to spring back around the marginal portions of the creel top essentially as shown in Fig. 5 embracing same and holding the rear portion of the blocks in position thereagainst. The spring tensioned front fastening means hereinabove described is thereafter connected with the front portion of the creel top A'' by positioning the hook formations 22a therearound as illustrated in Fig. 5. It will be noted that the downwardly extending flanges of the opening 11a formed in the bottom 11 of the 60 container extend through the fish port A' in the top of the creel.

Having thus described the present invention, what it is desired to secure by Letters Patent is:

1. A fishing tackle container attachable to the

upper marginal portions of a creel comprising a box conforming in shape to the conventional outline of the upper parts of a creel, means for supporting said box within the upper portion of a creel, and means, upon occasion, for attaching said box to the closed top of the creel comprising a pair of laterally sliding spring tensioned claws mounted on the bottom rear portion of said box suited to receiving and gripping the marginal portions of the creel top, and a spring tensioned hook mounted on the bottom front portion of said box engageable with the creel top front.

2. A fishing tackle container attachable to the upper marginal portions of a creel comprising a box conforming in shape to the conventional outline of the upper parts of a creel, means for supporting said box within the upper portion of a creel comprising downwardly extending lugs mounted on the sides of said box for receiving and embracing the upper parts of the creel sides; and means, upon occasion, for attaching said box to the closed top of the creel comprising a pair of laterally sliding spring tensioned claws mounted on the bottom rear portion of said box suited to receiving and gripping the marginal portions of the creel top, and a spring tensioned hook mounted on the bottom front portion of said box engageable with the creel top front.

3. A fishing tackle container attachable to the upper marginal portions of a creel comprising an 30 interiorly subdivided box conforming in shape to the conventional outline of the upper parts of a creel, an upwardly and backwardly swinging cover for said box hingedly mounted on the rear marginal portions thereof, means for yieldingly holding said cover in opened or closed position comprising a spring pressing element mounted upon the rear side of said box and a cam movable with said top engaging with said spring pressing element; said box and cover having a 40 vertically disposed passage extending therethrough registerable with the fish opening in the creel top; means for supporting said box within the upper portion of a creel; and means, upon occasion, for attaching said box to the 45 closed top of the creel.

4. A fishing tackle container attachable to the upper marginal portions of a creel comprising an interiorly subdivided box conforming in shape to the conventional outline of the upper parts of a creel, an upwardly and backwardly swinging cover for said box hingedly mounted on the rear marginal portions thereof, means for yieldingly holding said cover in opened or closed position comprising a spring pressing element 50 mounted upon the rear side of said box and a cam movable with said top engaging with said spring pressing element; said box and cover having a vertically disposed passage extending therethrough registerable with the fish opening 60 in the creel top; means for supporting said box within the upper portion of a creel comprising downwardly extending lugs mounted on the sides of said box for receiving and embracing the upper parts of the creel sides; and means, upon occasion, for attaching said box to the closed top of the creel comprising a pair of laterally sliding spring tensioned claws mounted on the bottom rear portion of said box suited to receiving and gripping the marginal portion of the creel top, 70 and a spring tensioned hook mounted on the bottom front portion of said box engageable with the creel top front.

MAURICE G. BEAL.
